PRINTER'S CHASE

Floyd C. Roueche, Los Angeles, Calif.

Application June 13, 1949, Serial No. 98,691

2 Claims. (Cl. 101—394)

1

This invention relates to a printer's chase. It is particularly applicable to the class of printer's chase that is used for setting up type for newspapers.

The primary object of my invention is to provide a printer's chase which is of relatively light weight construction as compared to the conventional chase that has been used for many years in the newspaper publishing industry. Such conventional chase embodies an integral frame of steel, weighing about sixty-five pounds, and extremely cumbersome to handle. This characteristic of the chase is particularly disadvantageous when the chase is being carried from place to place within a printing establishment, and when it is being stored within intervals of use.

An important object of the invention is to provide a chase that can be knocked down or disassembled into a number of constituent parts, and yet which, when assembled, has all of the strength and rigidity required for holding a full page of newspaper type in rigid, accurate, assembly.

Another object of the invention is to provide a printer's chase having improved lock-up mechanism. Another object is to provide a knock down printer's chase having lock-up mechanism which cooperates with the frame sections thereof to securely lock all parts of the chase in assembled relationship with a page of type supported therein. This characteristic of the invention is important for the reason that a large amount of work goes into the setting up of a page of type the size of a newspaper page, and any accidental loosening of the frame sections of the chase would be likely to result in a complete loss of this work, requiring the type to be set all over again. It will be understood in this connection that the type is held in the chase solely by the clamping of the type slugs between the frame sections of the chase, and the frictional engagement with each other and with the frame sections that thereby results. Any loosening of the frame sections of the chase would therefore be most likely to result in the entire assembly falling apart, making it necessary to start the type-setting operation over from the beginning.

In the invention, the lock-up mechanism cooperates with the frame sections of the chase to apply spreading pressure in two directions at right angles to each other, thereby securely locking the sections together.

A further object of the invention is to provide an improved lock-up actuator having a push-pull operation.

Another object is to provide an improved lock-

2

up mechanism in which the retracting function of the lock-up actuator may be dispensed with and in which the lock-up mechanism is adapted to automatically release as soon as the pressure of the actuator upon the wedge mechanism is relieved.

Other objects will become apparent in the ensuing specifications and appended drawings in which:

Fig. 1 is a plan view of a printer's chase assembly embodying my invention;

Fig. 2 is a side view of the chase;

Fig. 3 is an end view of the chase;

Fig. 4 is a detail sectional view of the lock-up actuator taken on the line 4—4 of Fig. 1;

Fig. 5 is a detail sectional view of a wedge unit of the lock-up mechanism taken on the line 5—5 of Fig. 4;

Fig. 6 is a detail sectional view of a modified form of the wedge unit; and

Fig. 7 is an exploded perspective view of a corner of the frame.

As an example of one form in which the invention may be embodied, I have shown in Figs. 1 to 5 inclusive a printer's chase comprising longitudinal and transverse frame bars 6 and 7 respectively, each constructed from a metal having a high strength-weight factor. I prefer to employ one of the known lightweight, high strength metals of the aluminum-magnesium alloy class, rather than the much heavier steel that is now employed in printer's chases.

The frame bars 6 and 7 are provided with interlocking mortise and tenon connections including tenons 8 on the ends of the longitudinal bar 6, receivable in mortises 9 on the ends of the transverse bars 7, and also including lug members 10 projecting from the tenons 8 and receivable in spaces 11 communicating with the mortises 9. Each tenon 8 and corresponding lug 10 collectively constitutes an L-shaped hook, and each mortise 9 and space 11 collectively constitutes a correspondingly L-shaped recess receiving such hook.

Each L-shaped recess 9, 11 is spaced from a respective end of a transverse bar 7 so as to define a head 12 which is connected to the body portion of the bar by a neck 13. The width of a head 12 is approximately half the width of a longitudinal bar 6. The hook 8, 10 is likewise approximately half the width of a bar 6 and is disposed at one side thereof, the other side of the bar being cut away to provide a space 17 to accommodate the head 12. The space 17 is defined at one end by a shoulder 14 which is adapted to abut against the inner end of the head 12,

while the lug 10 engages the inner vertical face of the neck 13. The lug 10 is spaced from the shoulder 14 by a notch 15 which is only slightly wider than the neck 13. Thus, in the assembled relation of the frame bars, the neck 13 is snugly received between the lug 10 and shoulder 14 and accommodated entirely in the notch 15. The width of the recess 9, 11 is only slightly greater than the width of the hook 8, 10 whereby the latter is snugly received between a shoulder 16 constituting the end of the central body portion of the bar 7, and an inner face of the head 12, said shoulder 16 and inner face comprising the side walls of the recess 9, 11. The shoulder 14 is engaged securely against the head 12. The under surface of the tenon 8 is engaged against the upper surface of the neck 13.

The lock-up mechanism comprises a bar 19 adapted to lie against the inner side of one of the frame bars 6, and a co-acting bar 18 adapted to engage a body of type which is indicated at 42 in Fig. 2. The bar 19 has in one side a plurality of recesses 21, each of which has one side constituting a ramp 22 against which a wedge pin 23 carried by the bar 18, is adapted to operate.

One of the important characteristics of the invention is simplicity and inexpensiveness of construction, coupled with reliable, efficient operation and durability under long periods of use. In the wedge mechanism, these objects are attained by utilizing the wedge pins 23 which may be constructed simply by cutting lengths from a round rod of metal which is preferably a metal different from that of the bar 18 (e. g. steel). The wedge pins 23 are mounted in the bar 18 simply by drilling sockets 24 in the bar 18, inserting the pins 23 in the sockets 24, drilling from side to side through the bar 18 a series of holes 25 centered with reference to sockets 24 and extending through pins 23, and inserting through the holes 25, locking pins 26. The sockets 24 are drilled at an angle disposed at 90 degrees to the ramps 22 and the ends of the wedge pins 23 may thus be fitted to the ramps 22 simply by cutting them off squarely.

The wedge bar 19 is moved by an actuator screw 27 having a smooth cylindrical shank journaled in a bearing bore 28 in a transverse frame bar 7; having a squared head 29 to receive a wrench; having a flange or washer 30 providing an end bearing abutment against a peripheral face of the frame bar 7; carrying a washer 31, pinned thereto by a pin 32, the washer 31 providing end bearing abutment against the inner face of frame bar 7; and having a threaded end portion 33 threaded into an internally threaded bore in bar 19 (Fig. 4). In prior push-pull actuator arrangements it is customary to utilize an actuator screw threaded through the transverse frame bar and having a head rotatably engaged in an open socket in one end of the wedging bar. The present improvement has the advantage of connecting the wedging bar to the frame through the actuator screw, avoiding the dropping of the wedging bar off the end of the actuator screw when the chase is being disassembled.

In Fig. 6 I have shown a modified form of wedging mechanism in which wedge pins 23a are pivotally mounted, upon pivots 35, in sockets 24a which are somewhat larger in diameter than the pins 23a. Each pivot 35 is slightly offset to one side of the axis of its socket 24a, so that the pin 23a may, when the chase is being locked up, bear against the near side of the socket 24a as indicated in Fig. 6, thereby to resist the turning moment in the direction indicated by arrow

36, imparted to it by ramp 22 of bar 19, as the bar 19 is moved in the lock-up direction indicated by arrow 37. This imparts to the pin 23a the function of a wedge which, cooperating with ramp 22 in the same manner as the pin 23 of Figs. 1 and 5, forces the bars 18 and 19 apart to lock up the chase.

Instead of the push-pull actuator screw of Figs. 1-5, this form of the invention utilizes a simple screw 27a which is threaded through frame bar 7a and has its inner end in abutting, bearing engagement against the end of wedge bar 19.

Upon backing off the screw 27a, the lateral pressure of the type against ramp bar 19, indicated by arrow 38, will, as the result of the pivotal connection of wedge pins 23a to wedge carrying bar 18, cause bar 19 to shift generally in a direction of circumferential movement of the points of bearing contact of the ends of wedge pins 23a against ramps 22 (a direction opposite to that indicated by arrow 36). This direction of shifting movement of bar 19 is indicated by arrow 39. Such shifting movement will automatically unlock the wedging mechanism without requiring the striking of a blow against an end of one of the wedging bars (a common procedure in conventional chases) or the application of retractor force to one of the wedging bars as in the operation of the form of the invention shown in Figs. 1-5.

In order that the unlocking may be smooth and positive, the corners of wedge pins 23a nearest the bottoms of recesses 21, are relieved as by chamfering circumferentially with reference to pivots 35. The chamfered corners of pins 23a will thus have rolling contact with ramps 22 at uniform radius so that there will be no resistance to the unlocking movement of bar 19 as described above.

A pair of clamp screws 40 are threaded through one of the bars 7. The clamp screws 40 function to engage a pressure bar 41 laid against one end of the body of type 42, and to transmit pressure through the bar 41 to the body of type.

In the use of my improved chase, the frame bars 6 and 7 are assembled upon a work table and the bar 18 is inserted in its proper place; the bar 19 is completely retracted to a point adjacent the inner side of the frame bar 7, and the bar 18 is shifted to a position adjacent the bar 19 with the wedge pins 23 received to the maximum extent in the recesses 21.

Type 42 is then arranged in the space within the chase, until the full body of type has been assembled. The pressure bar 41 is then laid between the clamp screws 40 and the adjacent end of the body of type 42, and the clamp screws 40 are advanced until the bar 41 makes light engagement with the body of type. The actuator screw 27 is then advanced, causing the ramps 22 to rise on the ends of wedge pins 23 and forcing the bar 19 inwardly against the side of the body of type 42. The screws 40 and 27 are then alternately tightened until the desired amount of pressure is applied to the body of type in both directions.

The compressive forces set up in the body of type 42 react against the frame bars 6 and 7 to establish pressure between the inner faces 41 of the heads 12 and the inner faces 43 of the tenons 8; and between the inner faces 44 of the lugs 10 (Fig. 5) and the inner side faces of the neck 13. Frictional engagement is established between these faces to an extent which securely locks the frame bars together at the corners of the chase, making it possible to transport the loaded chase

from the make-up table to the machine where a negative impression of the type is produced in a mat or matrix of papier mache into which the melted lead is poured to form one-half of a printing roll.

After the mat or matrix has been produced, the loaded chase may be returned to the place where the type slugs are to be removed from the chase and remelted for use in the slug-making machine. This is accomplished by backing off the screws 27 and 40 until the chase can be bodily lifted from the body of type or, if desired, removed therefrom piecemeal. Once the pressure between the joints has been removed, the bars 6 may be readily lifted away from engagement with the bars 7. On the other hand, if desired, the empty chase may be lifted bodily by grasping one of the bars 7 and tilting it up to a position in which it hangs suspended from said bars 7, and it may be carried in this manner back to the make-up table and placed in position to receive another body of type. When not in use, it is disassembled and the parts thereof may be neatly stacked in a compact bundle.

The use of magnesium-aluminum alloy has proven to be very satisfactory. The alloy has a strength factor comparable to that of steel, while the weight is considerably less. The alloy may be easily and accurately machined to the desired closeness of fit between the inner connecting parts. It is extremely durable.

Because of its knock-down characteristics, if one of the frame bars becomes battered beyond the point of usefulness, it may be replaced by a new bar without necessitating the replacement of the entire chase. This is a distinct advantage, since printers' chases are often roughly handled, and they are expensive.

I claim:

1. In a knock-down printer's chase: a frame including longitudinal bars and transverse bars; a pair of wedging bars one of which is provided with a series of recesses each having an inclined bottom wall constituting a wedging ramp and having parallel side walls, the other having a plurality of sockets disposed with their axes at right angles to said ramp; a plurality of wedge pins mounted in said sockets, extending into respective recesses, confined between said parallel walls thereof, and having bearing ends slidably engaging said ramps; and actuator means for shifting said wedging bars relatively longitudinally whereby to effect wedging action between said bearing ends and said ramps, resulting in spreading movement of said wedging bars, each pin being pivoted to a respective wedging bar at a point near the bottom of its respective socket, having an opposite end slidably engaging a respective wedging ramp, and adapted to engage one side of its socket for limiting its pivotal movement in the direction in which it tends to swing when being forced against said respective wedging ramp to develop spreading action between the wedging bars, said limiting action disposing said pins in wedging position in which

their longitudinal axes are substantially normal to their respective wedging ramps, said sockets being of larger diameter than said wedge pins whereby the latter in said wedging positions are spaced from the opposite sides of said sockets to

5 provide for lost motion return pivotal movement of the wedging pins away from said wedging positions in response to relative retracting movement of the wedging bars, whereby to readily relax wedging pressure between said wedging pins and ramps and thereby facilitate unlocking of the chase.

2. In a knock-down printer's chase: a frame including longitudinal bars and transverse bars; a 15 pair of wedging bars one of which is provided with a series of recesses each having an inclined bottom wall constituting a wedging ramp and having parallel side walls, the other having a plurality of sockets disposed with their axes at right angles to said ramp; a plurality of wedge pins mounted in said sockets, extending into respective recesses, confined between said parallel walls thereof, and having bearing ends slidably engaging said ramps; and actuator means for 20 shifting said wedging bars relatively longitudinally whereby to effect wedging action between said bearing ends and said ramps, resulting in spreading movement of said wedging bars, each pin being pivoted to a respective wedging bar at 25 a point near the bottom of its respective socket, having an opposite end slidably engaging a respective wedging ramp, and adapted to engage one side of its socket for limiting its pivotal movement in the direction in which it tends to swing 30 when being forced against said respective wedging ramp to develop spreading action between the wedging bars, the bearing ends of each pin being inclined at an acute angle to the axis of wedging pressure between the pin pivot and the point of 35 contact of said bearing end with the respective ramp, with said acute angle disposed on that side of said axis of pressure toward which the pivotal movement is limited as aforesaid, whereby, upon reverse actuation of said actuator means, 40 said wedging bars will automatically undertake relatively longitudinal shifting movement in the direction to relax the wedging pressure acting therebetween.
